ELECTRON BEAM TUBE

Ferenc Preisach and Imre Zakariás, Budapest,
Hungary, assignors to United Incandescent
Lamp and Electrical Company, Ltd., Újpest,
Hungary

Application March 23, 1939, Serial No. 263,708
In Germany March 29, 1938

3 Claims. (Cl. 250—151)

Our invention relates to electron ray valves, more especially of the kind in which means are provided for deflecting the electrons of the ray.

It is an object of our invention to improve this type of valves in several respects, as will appear more in detail as the specification proceeds.

As is well known, electrical alternating voltages can be amplified by directing the electrons of an electron ray in timely alternation from one collector electrode onto another by influencing deflecting members. If the voltage to be amplified is connected to the deflecting member and the anode current collected from one of the collector electrodes (the working anode), an amplified voltage can be produced on the loading resistance.

If the efficiency of such an arrangement is compared with that of the well known space-charge controlled screen grid valves, the following facts can be ascertained. If one succeeds in so far increasing the sensibility of the electron control (mutual conductance of the valve) by a suitable dimensioning of the deflecting control members, as is the case in space-charge controlled valves, it will be found that the inner resistance in the electron ray valve is considerably lower, so that an amplification such as is possible with a space-charge controlled screen grid valve, is not obtainable. On the other hand the electron ray valves with deflection control offer the basic advantage, as compared with the space-charge controlled valves, that the electrons are not braked, the electron paths being only deflected through small angles, whereby the formation of space-charge clouds in the high frequency field is avoided, which are known to involve certain disadvantages at higher frequencies. These disadvantageous effects are particularly known in the modern mixing valves (hexodes, octodes); the distribution control, by means of the outer control grid, which is employed in these valves, is not a deflection control, because here the paths of the electrons are bent completely, whereby disadvantageous phenomena arise.

The improved electron ray valve according to the present invention combines the advantages offered by the deflection control with the high amplification value of the space-charge controlled screen grid valves.

In the drawings affixed to this specification and forming part thereof a valve embodying our invention is illustrated diagrammatically by way of example.

In the drawings:

Fig. 1 is a diagram of connections of this valve, while

Figs. 2-5 show details of different arrangements of the screens and anodes.

Figs. 6 and 7 are diagrams showing further modifications of the valve according to this invention.

In all the figures K is the cathode, G the control grid, A₁ and A₂ acceleration and ray concentration electrodes, respectively, P₁ and P₂ deflecting electrodes, SG, SG₁ and SG₂ are screen grids, BG is the suppressor grid, A and A' are working anodes, HA is the auxiliary anode, S and S' are electrodes for concentrating the ray to about cathode potential. L₁ is the inductivity and C₁ the capacity of the input oscillation circuit, L₂ and C₂ the inductivity and capacity, respectively, at the output of the valve. C₃, C₄ and C₅ are bridging condensers, E is an anode voltage source, R a voltage divider resistance and St and St' are electron paths. On testing the inner resistance of the working anode A of an electron ray valve such as shown in Fig. 1, the following effects can be ascertained, which render the anode current dependent from the anode voltage:

1. Passage from the anode A to the control member P₁—P₁.

2. A secondary emission exchange between the working anode A and the auxiliary anode HA.

3. A deflection of the ray in the critical range at the passage of the bundle of rays St—St' (passage of current) from one anode to the other.

In order to avoid the first mentioned effect, it appears obvious to arrange a screen grid SG₁ in front of the anodes A—HA, as is usual in space-charge controlled electron valves. In analogy with the screen grid valves fitted with suppressor grids it is also advisable to avoid the exchange of secondary emissions by the insertion of a suppressor grid BG. The tests have however shown that by these obvious steps the inter-valve resistance cannot be increased sufficiently.

45 For it has been found that the differential inner resistance of the anode circuit in the critical range of passage of current drops by one-tenth, for instance from 500,000 ohm to 50,000 ohm in the case of an anode current of 3 milliampere.

50 Our invention is based on the perception that this electron-optical influence of the working anode on the inter-valve resistance is decisive and that it can be done away with by the screening methods according to this invention.

55 Arrangements of the screens and anodes em-

bodying this invention are shown in Figs. 2-5. In all these arrangements the working anode A is separated from the auxiliary anode HA by a screen grid SG, the working anode A being always arranged behind the auxiliary anode HA, if viewed in the direction of the ray St-St'.

If, in an arrangement such as shown in Fig. 2, the ray enters the critical range, if the mesh of the screen grid is sufficiently narrow, a change of the anode voltage becomes imperceptible at the point k.

In order to avoid an exchange of secondary emission with the screen grid SG, a suppressor grid BG is further inserted between the screen grid SG and the anode A in Fig. 3.

A simplified and yet highly effective arrangement is shown in Fig. 4, where the auxiliary anode HA and the screen grid SG form a mechanical and electrical unit, in which the surface of the auxiliary anode HA is continued by the surface of the screen grid SG₁, which may have the form of a wire-gauze or may be formed of windings. In consequence of this arrangement the potential is mainly determined, throughout the entire surface and therefore also at the critical point k, by the voltage of the auxiliary anode HA and depends from the anode voltage only in proportion to the passage from the anode A through the suppressor grid BG.

If it should prove necessary, a further screen grid SG₂ can be inserted between the auxiliary anode HA and the suppressor grid BG (Fig. 5).

In the combinations shown in Figs. 2, 3 and 5 the screen grid SG₁ can be connected with the auxiliary anode inside or outside of the valve.

With the arrangements according to this invention the amplification-factor of the valve can be increased to more than 20. However, such values are necessary in order to attain amplification factors above 500 and valve resistances above 100,000 ohm, in the case of anode currents above 1 milliampere, which is again necessary in order to obtain mutual conductance values above 1 mA/V.

The electron ray valve thus equipped can be fitted with one or a plurality of control members G in order to be able to use the valve as amplifier or mixing valve or control valve.

If it is desired to produce by means of an electron ray valve alternating anode currents of a magnitude similar to that of the usual space-charge controlled electron valves, the electron ray bundle must be produced by means of an electrode surface K of 10^{-1} cm.². In that case it is very useful to form the bundle normally to the longitudinal axis of a prismatic or cylindric cathode K and to subdivide it into two or more bundles, according to Figs. 6 and 7.

One may for instance operate by such an arrangement a mixing valve connection by arranging behind the cathode K a space-charge control G and then providing another deflection control as indicated for instance in Fig. 7 by the rods P₁-P₂.

While the screening system according to this invention is illustrated in Figs. 1-7 only with reference to the case where the concentration and deflection of the electron ray or bundle of electron rays is effected electrostatically, it is evident that the same arrangements will also bring forth the desired effect in the case of magnetic or mixed concentration and deflection of the electron ray or electron ray bundle.

Various changes may be made in the details disclosed in the foregoing specification without departing from the invention or sacrificing the advantages thereof.

We claim:

1. An electron beam tube comprising an electron emitting cathode, means for deflecting the electrons, and electrodes disposed normally to the direction of the electron beam as emitted from said cathode, including an auxiliary anode, a working anode, said anodes being arranged in consecutive parallel planes, the plane of said working anode being disposed to the rear of said auxiliary anode, and a grid structure adapted 15 to take up substantial current provided between, and in a plane parallel to the planes of, the two anodes for the purpose of substantially preventing any passage from the working anode to said deflecting means and any exchange of secondary 20 emission between the two anodes, whereby to render the electron paths and the inner resistance of the working anode substantially independent from changes of the anode potential throughout the range of operation.
- 25 2. An electron beam tube comprising an electron emitting cathode, means for deflecting the electrons, and electrodes disposed normally to the direction of the electron beam as emitted from said cathode, including an auxiliary anode, a working anode, said anodes being arranged in consecutive parallel planes, the plane of said working anode being disposed to the rear of said auxiliary anode, and a grid structure adapted to take up substantial current provided between the 30 two anodes for the purpose of substantially preventing any passage from the working anode to said deflecting means and any exchange of secondary emission between the two anodes, said grid structure comprising a screen grid attached to, and disposed in the plane of, said auxiliary anode so as to be located in front of said working anode, whereby to render the electron paths and the inner resistance of the working anode substantially independent from changes of the anode potential throughout the range of operation.
- 35 3. An electron beam tube comprising an electron emitting cathode, means for deflecting the electrons, and electrodes disposed normally to the direction of the electron beam as emitted from said cathode, including an auxiliary anode, a working anode, said anodes being arranged in consecutive parallel planes, the plane of said working anode being disposed to the rear of said auxiliary anode, and a grid structure adapted to take up substantial current provided between the two anodes for the purpose of substantially preventing any passage from the working anode to said deflecting means and any exchange of secondary emission between the two anodes, said grid structure comprising a screen grid attached to, and disposed in the plane of, said auxiliary anode so as to be located in front of said working anode, a second screen grid and a suppression grid arranged in consecutive parallel planes between, and in parallel to the planes of, said anodes, whereby to render the electron paths and the inner resistance of the working anode substantially independent from changes of the anode potential throughout the range of operation.
